UNITED STATES PATENT OFFICE.

GEORGE H. BARTLETT, OF SAN FRANCISCO, CALIFORNIA, ASSIGNOR TO NATIONAL PAPER PRODUCTS CO., OF SAN FRANCISCO, CALIFORNIA, A CORPORATION OF CALIFORNIA.

PAPER-BOX-FORMING MACHINE.

1,305,511.

Specification of Letters Patent. Patented June 3, 1919.

Application filed February 14, 1918. Serial No. 217,064.

To all whom it may concern:

Be it known that I, GEORGE H. BARTLETT, a citizen of the United States, residing in the city and county of San Francisco and 5 State of California, have invented new and useful Improvements in Paper-Box-Forming Machines, of which the following is a specification.

This invention relates to paper box machinery and particularly pertains to a machine for forming paper boxes of irregular shapes.

The principal object of this invention is to provide a machine adapted to act in conjunction and continuously with a paper tube machine to shape the freshly wrapped tube to produce box walls of various configuration, it being common to roll the tube cylindrical.

In carrying out the present invention it is intended to provide a forming machine having a central mandrel or core in longitudinal alinement with the cylindrical mandrel of a tube forming machine and adapted to receive the tube as it passes off from the end 25 of the cylindrical mandrel. The core is especially formed so that the tube may be shaped upon it to assume elliptical or polygonal shaped boxes, the heights of which are determined by cutting mechanism operating 30 as the formation of the boxes progresses.

The invention is illustrated by way of example in the accompanying drawings, in which—

Figure 1 is an enlarged view in side elevation illustrating the vital elements of the forming machine in their coöperative relation to each other.

Fig. 2 is an enlarged fragmentary view in section illustrating the end of the forming 40 mandrel and indicating the circulation of a heating fluid therethrough.

Fig. 3 is a view in plan illustrating the principal parts of the forming machine.

Fig. 4 is a view in transverse section as 45 seen on the line 4—4 of Fig. 3 disclosing the relation of the forming core to the ironing rollers and further indicating the manner in which they are simultaneously driven.

Fig. 5 is a view in transverse section as 50 viewed on the line 5—5 of Fig. 3 disclosing the adjustment provided the supports of the ironing rollers whereby tube walls of varying thickness may be accommodated.

Fig. 6 is a diagrammatical view illustrat-

ing the gear relation existing between the 55 tube wrapping machine and the forming machine with which the present invention is concerned.

Fig. 7 is an enlarged view in plan illustrating by section and elevation the tube 60 wrapping machine which produces the tube subsequently treated by the forming machine.

Figs. 8 and 9 are views in elevation illustrating the outer appearance of the cylindrical tube as it comes from the wrapping machine.

Figs. 10 and 11 are views in elevation illustrating the outer appearance of the tube after having been formed square upon the 70 forming machine.

Figs. 12 and 13 are sectional views disclosing other forms which the paper tubing might be made to assume.

Referring more particularly to the drawings, 75 10 indicates a base to which parallel longitudinally extending angle plates 11 and 12 are fastened by bolts 13. The formation of these plates is particularly disclosed in Figs. 4 and 5 where it will be seen that their vertical legs are parallel and spaced from each other and their horizontal legs are outwardly turned in opposite directions and lie in the same horizontal plane. Adjusting bolts 14 extend through the vertical portions of these 80 angle plates and are distributed at intervals therealong. These bolts are fitted with lock nuts 15, one of which is disposed upon each side of each plate and provides lateral adjustment of the plates in relation to each 85 other when the screws 13 are loosened. Adjustably fastened to the outwardly extending leg portions of these plates are vertical 90 adjusting bolts 16 and 17 which are provided with complementary lock nuts 18 at their 95 opposite ends. The upper ends of these bolts extend through horizontal leg portions of upper angles 19 and 20 which are held by the bolts in horizontal parallel relation to the adjacent leg portions of the lower angles. The vertical legs of the upper angle 100 plates are parallel and are in vertical alinement with similar legs of the lower plates, being held in spaced relation to each other by means of adjusting bolts 21 having complementary lock nuts 22 serving the same 105 purpose as the bolts 14, 16 and 17.

Referring particularly to Fig. 5, it will

be seen that the angle plates when assembled as described will assume a Maltese cross shape and will provide a longitudinal central opening through which a hollow forming mandrel 23 may extend. This mandrel is full floating and is thus free to properly adjust itself in relation to the complementary sets of ironing rollers, sets 24 and 25 being disposed between the vertical legs of the angle plates and upon the upper and lower sides of the mandrel while sets 26 and 27 are disposed between the horizontal legs of the angle plates and upon the opposite vertical sides of the mandrel. These sets are here shown as comprising three rollers, although it will be understood that the number will be made to agree with the use to which the machine is put.

Each of the rollers is mounted upon an individual shaft extending through bearings carried by the various legs of the angle plates and are simultaneously driven by a driving mechanism. This mechanism comprises a main drive shaft 28 extending in longitudinal alignment with the machine and rotatably held within bearings secured to one of the angle plates thereof. A pulley 29 is fastened to one end of the shaft to receive motive power while gears 30 are disposed at intervals along the shaft and simultaneously mesh with gears 31 upon vertically disposed jack shafts 32. In the present instance, these secondary shafts 32 form the main shafts upon which the ironing rollers 23 are mounted. Driving gears 33 and 34 are secured to the jack shafts upon opposite sides of the ironing rollers and mesh with gears 35 and 36 respectively. These last-named gears are fixed to the horizontal shafts which carry the ironing rollers 24 and 25. Gears 37 are fastened at the opposite ends of the shafts of rollers 24 and are in mesh with complementary gears 38 driving the shafts of rollers 27. It will thus be seen that rotation of the main shaft 28 will cause simultaneous uniform rotation of all of the spindles which carry the various ironing rollers disposed upon the opposite sides of the mandrel.

Referring particularly to Fig. 1, it will be seen that the mandrel here shown is square in sectional configuration throughout the major portion of its length and that the square merges into a cylindrical portion at one end of the mandrel. It will further be noted that the mandrel is hollow and is provided with a centrally disposed inflow pipe 39 which will conduct steam into the mandrel and which is telescoped within an exhaust pipe 40 adapted to complete the circulation of the heating fluid. By this means the core or mandrel 23 may be heated to a desired temperature and will thus facilitate in forming the box blanks without cracking the stock from which they are made. Conduits 39 and 40 are concentric with the common longi-

tudinal axis of the floating core forming machine and the cylindrical mandrel 41 of the wrapping machine.

The wrapping machine is indicated in a diagrammatical manner in Fig. 7 where it will be seen that a base 42 is provided upon which the mandrel is supported. This mandrel is adapted to receive overlapping paper blanks 43 and 44 which wrap in overlapping fashion upon the mandrel and upon their separate convolutions. A series of driving belts 45 are wrapped around the mandrel and the partly formed tube to form power transmitting means for feeding the paper to the mandrel, wrapping it therearound and advancing it therealong so that the formed tube will be continuously forced off of one end of the mandrel and on to the adjacent cylindrical end of the forming core 23.

A rotating cutter 45' is mounted for slideable movement in a position to sever the wrapped blank into desired lengths as it is carried from the wrapping machine to the forming machine.

In operation paper blanks 43 and 44 are carried on to the cylindrical mandrel 41 and wrapped therearound, it being understood that their inner faces are treated with glue prior to the wrapping operation. As the belts 45 are driven the paper is tightly drawn around the mandrel and assumes an outer and an inner wall glued together, the seams of which occur midway the length of the two strips of paper and are thus covered and form a continuous two-ply wall. It will be understood that walls of other thickness may be formed with this machine and that the present invention is in no way limited to the construction or operation of a tube wrapping machine.

As the tube is formed it is projected off of the end of the cylindrical mandrel 41 and on to the adjacent end of the mandrel 23. The cutting member 45', which is disposed between the adjacent ends of these mandrels, may be swung into engagement with the tube and will sever it into desired lengths corresponding to the heights of the boxes to be formed. These lengths of cylindrical tubing are then carried over the cylindrical end of the core 23 and will be fed on to the square portion of the core by the various ironing rollers 24 to 27, inclusive, it being understood that the core is supported in its substantially centered position by means of a supporting roller 46 rotatably mounted beneath the core and upon a bearing 47 adjustably secured to the base 10. As the ironing rollers force the tube sections along the square core 23 the tube will be stretched and shaped to the sectional contour of the core and when it passes from the opposite end thereof will be permanently formed into the shape desired. It will thus be seen that as the tube has been freshly made and the glue

binding it has not yet set the heat of the core 23 and the pressing action of the ironing rollers will cause the various thicknesses of the tube wall to be properly stretched and 5 shaped in relation to each other as they adhere thereto. By a change in design in the sectional formation of the core 23 and the arrangement of the ironing rollers boxes of various shapes may be made in a continuous 10 operation and in conjunction with a tube wrapping machine.

It will thus be seen that the device here disclosed is simple and direct in its operation, is not liable to become inoperative and 15 may be readily adapted for forming box blanks of various shapes.

While I have shown the preferred construction of my invention as now known to me, it will be understood that various 20 changes in the combination, construction and arrangement of parts may be made by those skilled in the art without departing from the spirit of the invention as claimed.

Having thus described my invention, what 25 I claim and desire to secure by Letters Patent is:

1. A paper box forming machine comprising yieldable supporting means for receiving a tubular box blank from a paper tube 30 wrapping machine and forming means adapted to shape the blank to the outer configuration of the support.

2. A paper box forming machine comprising a floating core over which a tubular box 35 blank is drawn as the same leaves a paper tube wrapping machine and ironing rollers adapted to shape the blank to the outer configuration of the core and to advance it therealong.

40 3. A paper box forming machine comprising a floating core arranged to receive a tubular box blank from a paper tube wrapping machine, a rotary forming means mounted in relatively fixed bearings and 45 adapted to shape the blank to the outer configuration of the core, the latter being automatically adjusted through its floating action to accommodate box blanks having walls for the varying thickness.

50 4. In combination with a paper tube wrapping machine having a hollow mandrel and a paper box forming machine having a hollow core arranged to receive a tubular box blank from the mandrel of the paper 55 tube wrapping machine, formed of means adapted to shape the blank to the outer configuration of a core, and heating means common to the core and the mandrel.

5. In combination with a paper tube 60 wrapping machine having a hollow mandrel and a paper box forming machine having a floating hollow core arranged to receive a tubular box blank from the mandrel of the paper tube wrapping machine, formed of

means adapted to shape the blank to the outer configuration of a core, and heating means common to the core and the mandrel.

6. In combination with a paper tube wrapping machine having a hollow mandrel and a paper box forming machine having a 70 floating hollow core arranged to receive a tubular box blank from the mandrel of the paper tube wrapping machine, formed of means adapted to shape the blank to the outer configuration of a core, and heating 75 means common to the core and the mandrel and arranged to permit the floating action of the said core.

7. In combination with a paper tube wrapping machine having a hollow mandrel 80 and a paper box forming machine having a floating hollow core arranged to receive a tubular box blank from the mandrel of the paper tube wrapping machine, formed of means adapted to shape the blank to the outer configuration of a core, and heating 85 means common to the spindle and the core and arranged within and connecting with the said mandrel and core without interfering with the floating action of the latter. 90

8. In a paper box forming machine, a tubular floating core, means for heating said core without affecting the floating action of the same, a series of ironing rollers arranged around the core and adjacent thereto 95 whereby a box blank slipping over the core will be caused to conform thereto by the pressure of the rollers.

9. In a paper box forming machine, a tubular floating core arranged to receive a 100 tubular box blank from a paper tube wrapping machine, means for heating said core without affecting the floating action of the same, a series of ironing rollers arranged around the core and adjacent thereto 105 whereby a box blank slipping over the core will be caused to conform thereto by the pressure of the rollers, and means for simultaneously driving the rollers to advance the blank along the core. 110

10. In combination with a paper tube wrapping machine, a paper box forming machine, including a floating core arranged to receive a tubular box blank from the said paper tube wrapping machine and forming 115 rollers mounted in relatively fixed bearings and coöperating with the core to shape the blank to the outer configuration of the latter.

11. In combination with a paper tube wrapping machine, a floating shaping core 120 in longitudinal alignment therewith and over which the tube is carried as made by the wrapping machine and ironing rollers mounted in relatively fixed bearings adapted to press the side walls of the tube against 125 said core to cause the tube to assume the formation of the outer surface of the core.

12. A box forming machine comprising a

base, a series of separate frame members carried thereupon, means for adjusting said frame members in relation to each other and the base, a series of ironing rollers carried by 5 the various frame members, driving means therefor and a core extending longitudinally of the frame members and surrounded by the various rollers whereby a paper box blank may be pressed by the rollers against

the outer surface of the core to assume the 10 shape thereof.

In testimony whereof I have hereunto set my hand in the presence of two subscribing witnesses.

GEORGE H. BARTLETT.
